(57) **CLAIM**

The ornamental design for a compression sock, as shown and described.

DESCRIPTION

FIG. 1 is a first isometric view of a compression sock in an environment of use, in accordance with our design;

FIG. 2 is a front view of the compression sock of FIG. 1;
FIG. 3 is a rear view of the compression sock of FIG. 1;
FIG. 4 is a right-side view of the compression sock of FIG. 1;

FIG. 5 is a left-side view of the compression sock of FIG. 1;
FIG. 6 is a top view of the compression sock of FIG. 1;
FIG. 7 is a bottom view of the compression sock of FIG. 1;
FIG. 8 is a second isometric view of the compression sock of FIG. 1;

FIG. 9 is an isometric view of a foot arch pad cushion forming a portion of the compression sock of FIG. 1 shown removed for clarity of disclosure;

FIG. 10 is a left-side view of the foot arch pad cushion of FIG. 9;

FIG. 11 is a right-side view of the foot arch pad cushion of FIG. 9;

FIG. 12 is a rear view of the foot arch pad cushion of FIG. 9;

FIG. 13 is a front view of the foot arch pad cushion of FIG. 9;

FIG. 14 is a top view of the foot arch pad cushion of FIG. 9;

FIG. 15 is a bottom view of the foot arch pad cushion of FIG. 9;

FIG. 16 is an isometric view of a foot arch pad forming a portion of the compression sock of FIG. 1, partially shown in FIGS. 1, 2, 3, and 5, shown removed for clarity of disclosure;

FIG. 17 is a left-side view of the foot arch pad of FIG. 16;
FIG. 18 is a right-side view of the foot arch pad of FIG. 16;

FIG. 19 is a front view of the foot arch pad of FIG. 16;
FIG. 20 is a rear view of the foot arch pad of FIG. 16;

FIG. 21 is a top view of the foot arch pad of FIG. 16 including the foot arch pad cushion of FIG. 9 shown removed from the compression sock for clarity of disclosure;

FIG. 22 is bottom view of the foot arch pad and cushion of FIG. 21;

(Continued)

FIG. 23 is an isometric view of the foot arch pad cushion of FIG. 9 partially inserted in the foot arch pad of FIG. 16; FIG. 24 is an isometric view of the foot arch pad and cushion of FIG. 21; FIG. 25 is a right-side view of the compression sock of FIG. 1, shown with the foot arch pad cushion and the foot arch pad removed, in a flat state with the two straps in a stacked position; FIG. 26 is a right-side view of the compression sock of FIG. 1 with the two straps in an unstacked position; FIG. 27 is a right-side view of the compression sock of FIG. 1 in a flat state with the two straps in a stacked position and with the foot arch pad and cushion of FIGS. 21 and 24 on a top one of the two straps; and, FIG. 28 is a right-side view of the compression sock of FIG. 1 with the two straps in an unstacked position and with the foot arch pad and cushion of FIGS. 21 and 24 on a top one of the two straps.

In FIG. 1, the broken lines illustrate a human foot and leg that form no part of the claim; all other broken lines in the drawings illustrate portions of a compression sock that form no part of the claimed design.

1 Claim, 13 Drawing Sheets
